CLAIM

The ornamental design for a truncated asymmetric bandolier, as shown and described.

DESCRIPTION

FIG. 1 is a front plan view of a truncated asymmetric bandolier, showing a top zipper pocket along a central portion, and further showing optional front pockets and webbing which is indicated in phantom lines;

FIG. 2 is a rear plan view of the truncated asymmetric bandolier of FIG. 1;

FIG. 3 is a right front perspective view of FIG. 1;

FIG. 4 is a left front perspective view of FIG. 1;

FIG. 5 is a right rear perspective view of FIG. 1;

FIG. 6 is a left rear perspective view of FIG. 1;

FIG. 7 is a front plan view of the truncated asymmetric bandolier of FIG. 1 wrapped around the bodice of a mannequin; and,

FIG. 8 is a rear plan view of FIG. 7.

The broken lines showing the webbing and adjustable buckle, the zippers for the optional front pockets, the stitch lines and the position, number and size of these elements relative to the claimed design and any other broken lines (e.g. the mannequin) are to show the environment only and are not part of the claimed design itself.
